UNITED STATES PATENT OFFICE.

ELMER A. FARMER, OF MONTREAL, QUEBEC, CANADA.

SOUND-REPRODUCING MACHINE.

Application filed February 9, 1924. Serial No. 691,681.

To all whom it may concern:

Be it known that I, ELMER A. FARMER, of the city of Montreal, Province of Quebec, Dominion of Canada, a citizen of the United

5 States, have invented certain new and useful Improvements in Sound-Reproducing Machines; and I do hereby declare that the following is a full, clear, and exact description thereof.

10 My invention relates to sound reproducing machines of the type including in its operating mechanism a friction driving disc and a roller in rotative relation therewith, one being operated by the motor and transmitting movement to the other and through it to the turn table; and it also relates to the mechanism for controlling the time of the sound reproduced, and the means for starting and automatically stopping the machine.

15 The object of my invention is to simplify the construction of machines of this type and render the operation more uniform and at the same time reduce the friction in the operating and controlling parts thereby increasing the efficiency and making the control more sensitive.

20 A feature of the invention is a complete electrically operated driving unit which may be readily installed in any of the standard makes of machines of this type.

25 Further features are an improved mounting of the friction roller and turn table shaft; mechanism for obtaining fine adjustment of the speed of rotation of the turn table; and sensitive mechanism for starting and automatically stopping the machine.

30 The last-mentioned mechanism is so constructed and arranged that an instantaneous stop is effected precisely at the point of adjustment.

35 For full comprehension, however, of my invention reference must be had to the accompanying drawings in which similar reference characters indicate the same parts and wherein:

40 Figure 1 is a horizontal sectional view taken on line 1—1 Figure 2 illustrating particularly the relative positions of the parts of my improved sound reproducing machine;

45 Figure 2 is a vertical sectional view taken on line 2—2 Figure 1 illustrating particularly the operative connection between the motor and turn table shaft and the particular mounting of the motor and turn table shafts;

Figure 3 is a fragmentary view of one corner of the case of the machine and illustrating particularly the time control;

Figure 4 is a vertical sectional view of 60 the time control shaft mounting;

Figure 5 is a fragmentary plan view of the motor board with starting and automatic stopping devices mounted thereon;

Figures 6, 7, 8, 9 and 10 illustrate in 65 detail the several parts of this starting and automatic stopping mechanism;

Figures 11 and 12 are side elevations thereof looking from different angles;

Figures 13 and 14 illustrate the manner 70 in which the automatic stop is adjusted;

Figure 15 is a side elevation of the tone arm with the trip of the automatic stopping mechanism mounted thereon;

Figure 16 is a fragmentary plan view of 75 the automatic starting and stopping mechanism;

Figure 17 is a detail plan view of a modified means for adjusting the speed of rotation of the turn-table; and 80

Figure 18 is a detail view of the means for securing the time control shaft in position:

The entire mechanism constituting this invention is assembled as a unit which may 85 be installed in practically all standard makes of machines of this type in substitution for the turn-table driving mechanism which usually is spring operated. Figure 2 illustrates the manner in which the unit is 90 mounted in place, the body of the machine being indicated in dotted lines and the unit in full lines. The unit comprises parts located below the motor board consisting of a supporting frame and motor with friction 95 drive and mechanism for adjusting speed of rotation of the turn-table and mechanism located above the motor board consisting of a comparatively large circular carrier plate and starting and stopping mechanism 100 mounted thereon and a turn-table which of course is detachable.

The friction drive between the motor and turn-table shaft is so constructed and arranged that maximum precision of operation with minimum resistance to adjustment axially relatively to the shaft is obtained.

105 The motor is indicated at 2 and is suspended from the supporting frame 50 in a similar manner to that described in my 110 pending application Serial No. 534,252 with the shaft 2^a disposed horizontally. One

end of the latter is rotatably mounted in a hub 3^a forming a component part of the motor case 3. This hub is bored axially to receive the shaft, and bushings 3^b of Babbitt metal are inserted in each end of the boring thus formed, that portion of the boring between the bushings having a larger diameter to provide a lubricating chamber 3^c with which a vertical supply duct 3^d communicates. The armature or rotor as indicated at 4 is secured upon the extreme inner end of the shaft and prevents axial displacement of the latter in one direction while displacement in the reverse direction is prevented by a collar 17 fixed upon the shaft by a set screw 18 adjacent a Babbitt metal washer 18^a mounted in the motor case. That portion of the motor shaft which projects outwardly from the motor case as at 6 is slotted or grooved longitudinally as at 6^a to receive a key or lug 7^a carried by a sleeve 7 which is mounted upon the shaft and in telescopic relation therewith, the key and slot limiting the extent of axial travel of the sleeve upon the shaft. This sleeve has a pair of parallel encircling flanges 8 and 9 between which a friction roller 2 preferably of soft rubber is fixed, the roller being rotatable with the sleeve and adapted to frictionally engage a disc on the turn-table shaft to be presently described. The end of the sleeve farthest from the motor is provided with a rawhide tip or point 10 and a helical spring 14 contained within the sleeve 7 bears between this tip and the adjacent end of the motor shaft for the purpose of imparting to the sleeve a tendency to assume a position with the key 7^a engaging the outer end of the slot 6^a. The means for adjusting the roller axially along the motor shaft consists of a shaft 20 supported in the frame 50 through a hole in which it projects. This shaft is supported in place, against downward movement, by a displaceable suspending flange in the form of a horse-shoe plate 21 straddling the shaft in engagement with slots 22 on opposite sides of the latter. The suspending plate is retained against movement by a cupped washer 23 slipped onto the shaft before the horse-shoe plate is inserted to position, the latter being so fashioned and the cupped washer being of such diameter that the cup receives the plate when set in place with the shaft producing downwardly in the hole of the frame. It then rests on the cupped washer 23 and the suspending plate suspends it in position with freedom to rotate. A short distance below the frame the shaft is encircled by a comparatively heavy expansile spring 24. A second horse-shoe plate 26 straddles the shaft in engagement with a pair of slots 27 in the opposite sides of the shaft and a cupped washer 28 covers this plate while the spring 24 bears with considerable ten-

sion between the washer 28 and the underside of the frame to yieldingly resist rotation of the shaft 20. The upper end of the shaft projects upwardly through an opening 29 in the motor board and is squared as at 30 to receive one end of an adjusting arm 31 which has an opening for the purpose. The other end of this arm carries a pointer 32 and a finger hold 33, the pointer being movable across a graduated plate or dial 34 which may be detachably secured either to the plate 62 or the motor board by screws 34^a and nuts 34^b. The graduations of the plate indicate different degrees of speed at which it is desired that the machine operates. The lower end of the shaft 20 carries a resilient curved arm 35 fastened in place in a recess 36 by a screw 37. This arm is preferably constructed of spring steel and it extends from the shaft to position to have its face lie at right angles to the axis of the sleeve 7 and in engagement with the point 10. By moving the speed adjusting arm 31 the shaft 20 is rotated against the resistance of the spring which may turn with it and the arm 35 either moves the sleeve 7 and the roller against the spring 14 or permits this latter spring to move the roller in the opposite direction.

This roller rotates in frictional rotative engagement with a driving disc 40. The frame 50 is cast with a downwardly extending conical bearing 51 in which is set a brass or bronze bushing 52 extending from the bottom of the bearing to within a short distance from the top while the upper end of the boring is enlarged to provide a seat for a lubricating washer 52^a upon which, in turn, is seated a Babbitt metal washer 52^b having a convex top. The shaft 300 has a rigid collar 53 which rests on the top of the last-mentioned washer while the cupped washer indicated at 54 is set in the frame and encircles the shaft to retain lubricant inserted in the space 55 above the collar 53. The portion of the shaft within the bushing is chambered as at 56 to also hold lubricant while the lower end of the shaft is reduced in diameter and screw-threaded as at 57 thus providing a shoulder 58. The disc 40 is preferably constructed of cast-iron with an integral hub 40^a and is fastened on this diminished portion of the shaft by a nut 60 which is screwed upon the shaft and clamps the hub of the disc tightly against the shoulder 58. The upper end of the shaft detachably carries the usual turn table 61.

The mechanism for starting and automatically stopping the machine comprises a unit which is secured upon the circular attachment plate 62 beneath the turn-table and which consists of a switch, means for closing the switch, means for retaining the switch closed and sensitive means for auto-

matically opening the switch, a trip device mounted upon the tone arm and movable in unison therewith coacting with the last-mentioned means in the automatic stopping 5 of the machine.

The individual parts of the unit are mounted upon a carrier plate 70 removably secured upon the plate 62 as at 71, and having a lateral extension 72 upon which the 10 switch 73 is secured. This switch consists of a block of insulation having a fixed contact 74, a spring contact 75' movable to and from engagement therewith and four terminals 75, 76, 77 and 78, the first two having 15 the leads 79 of the main circuit connected thereto and the second two the leads 80 of the motor circuit.

The means for moving the spring contact 75' into engagement with the fixed contact 20 74 consists of a cam 81 of insulation which is superimposed upon and rotatable in unison with the pivoted end of the manually operated starting and stopping lever 82, the free end of which protrudes beyond the 25 periphery of the turn table, the pivoted end being of substantially disc form as at 82' and, with the cam, being rotatably secured upon the carrier plate by a headed stud 83. The carrier plate 70 is also extended beyond the 30 periphery of the turn-table as at 84 and bears the word "On" and "Off" indicating the starting and stopping positions of the lever 82.

The disc-like end 82' of the latter is provided with an angular extension 85 in which a friction stop 86 of leather or other material having similar properties is mounted, the stop being adapted when the lever 82 is in the "off" position with the switch open, 40 to bear against the inner face of the peripheral flange 87 on the turn-table and prevent rotation of the latter. Movement of the lever 82 to the "on" position simultaneously moves the stop away from the flange and 45 closes the switch, setting the motor in motion.

In order to limit the throw of the lever 82 when being moved to the "on" position for the purpose of protecting the spring 50 contact and preventing the extension 85 engaging the latter and causing a short circuit, the carrier plate has a lug 88 which is extended upwardly between the contact and the extension forming an abutment in the 55 path of the latter.

The throw of the lever in the opposite direction is limited by the free end of trigger arm 90. This trigger is tangentially disposed relatively to the disc end of the lever 60 and is adapted to retain the latter in position closing the switch. It is constituted by the longer arm of a bell-crank lever pivoted upon the carrier plate as at 91, the short arm being indicated at 92 and 65 of greater width than the trigger arm.

The latter is tapered to a blunt point forming a pawl 91' which bears against the edge of the disc end 82' of the lever 82 and is adapted to snap into position engaging a tooth 100 on the disc when the lever 82 is 70

moved to the "on" position with the consequent closing of the switch, this engagement of the pawl with the tooth holding the switch closed. In sound reproducing machines heretofore in use having automatic stops it 75 has not been possible to effect a stop at the exact point at which the stop was set, the stoppage usually occurring several grooves ahead of such point. This defect is overcome in the present invention by so constructing the trigger arm 90 and tooth 100 that the former assumes exactly the same position when maintaining the lever 82 in the "on" position as it does when the lever is in the "off" position. The importance of 80 this positioning will be realized when it is explained that the lever 82 is in the "off" when the manual adjustment of the stop is effected whereas the lever will be moved to the "on" position before such stop will be 85 called upon to perform its function so that it is essential that the position of the trigger arm 90 be undisturbed by the movement of the lever 82. To this end the disc and lever are notched behind the tooth 100 to 90 provide an abutment edge 82^b, which when the lever is in the "off" position, presents an abutment to the trigger arm coinciding with that presented by the disc 82' and the 95 face 100^a of the tooth when the lever is in the "on" position, the longer side 100^b of the tooth and the adjacent side 91^a of the trigger arm being correspondingly curved to facilitate this positioning. The engagement between tooth 100 and the pawl 91' 100 is such that although it will positively retain the lever 82 in the "on" position, if at any time during the playing of the record it is desired to stop the machine, this may 105 be readily accomplished by moving the lever to the "off" position, the end of the pawl simply riding over the tooth 100 when pressure is exerted upon the lever 82.

In order to yieldingly maintain the trigger in engagement with the disc 82' without detracting from its sensitivity to the influence of the automatic stopping means it is connected to the disc 82' by a tensional spring 95, the points of connection being constituted by lugs 96 and 97, one being 110 located on the side of the disc farthest from the trigger and the other being located upon the latter at a short distance from its free end.

The relative positioning of these lugs is 115 such that with the lever in the "off" position a straight longitudinal pull is exerted upon the trigger, the spring being disposed parallel thereto. When the lever is moved to the "on" position, however, the spring as 120 125

sumes a position at a very slight angle to the trigger and consequently exerts a combined longitudinal and lateral pull thereon which causes it to shift laterally to position 5 in front of the tooth 100. The lateral pull is so slight, however, that the slightest thrust on the short arm 92 obtains an immediate response in the release of the lever 82. Movement of the trigger away from the lever is limited by a lug 101 on the carrier plate.

It will be observed that the spring in addition to its functions above stated exerts tension upon the lever 82 and its associated 15 parts and consequently when the trigger in the releasing operation which I will presently describe is moved to position clear of the tooth 100 the lever will at once snap back to the "off" position. The automatic release of the trigger for the purpose of stopping the machine is effected by trip mechanism which acts upon the short lever arm 92.

This mechanism comprises a member 105 hinged upon the free end of such arm and forming an extension thereof, an abutment link 107 pivoted as at 108 upon the free end of the extension member and a trip arm 109 mounted upon the tone arm 110. The arm 92 is upwardly offset as at 112 to accommodate the member 105 which is hinged to its underside and an insulating washer 113 is inserted therebetween. The hinge pin or stud 114 is provided with a head 115 and is straddled by a spring horseshoe washer 116 inserted between the head and the arm, displacement of the spring being prevented by a locking lug 117 engaging a notch 118 therein. The purpose of the spring is to produce a frictional grip between the arm 92 and its member 105 which will transmit a releasing thrust on the latter to trigger arm 90 and overcome the lateral pull of the spring 95, at the same time permitting of 40 easy adjustment to any desired position. A lug 105' is formed on the member 105 and is adapted to engage the adjacent portion of the arm 92 where the member is in its extreme position to the right.

50 The abutment link 107 unlike the other parts of this mechanism already alluded to is not concealed beneath the turn-table but is positioned between the latter and the base of the tone arm and is adjustable upon the stud 108. It is curved concentrically to the centre upon which the tone arm swings and its elongated slot 120 receives the downwardly bent end 121 of the trip arm 109, the latter being secured by screws 122 upon the tone arm.

55 In order to adjust this trip mechanism the tone arm is moved to the point at which it is desired to stop the machine as indicated in Figure 14 and the abutment link 107 is then shifted to the right until the trip

arm engages the left end of the slot 120. The tone arm is subsequently returned to its starting position and the machine is ready to be operated.

In order to provide means for controlling 70 the torque of the motor shaft for the purpose of supplementing the adjustment of the speed of rotation of the turn-table a rheostat or variable resistance 200 is included in the motor circuit. This rheostat 75 is of the usual construction and consists of a resistance tapped at intervals and connected to studs 201 with which a contact arm 202 is adapted to make contact. This arm is insulated from and operated by an adjusting arm 203 fulcrumed as at 204 and having a pointer 205 movable across a dial or graduated plate 206. The latter is provided with an adjustable stop or abutment 207 so that once the desired position of the pointer is 80 ascertained the stop may be fixed to render further reading of the graduation unnecessary. The resistance is so tapped that the movement of the contact 202 from one stud 85 to the next stud causes an increase or decrease of twenty volts. This may be varied, 90 however, if desired.

In the embodiment illustrated there are seven studs with which the contact arm 202 may engage. The adjusting arm 203 has a 95 range of movement from the "neutral" position to "F" (fast) position as indicated in Figure 17. The first stud engaged by the arm when moving from the "neutral" to the "S" (slow) position does not include the 100 resistance and consequently the maximum voltage preferably 110 volts is obtained which sets the motor armature in motion. Continued movement of the arm brings it into engagement with the second stud 105 which includes the entire resistance in the circuit and reduces the voltage to 20 volts. This is the slowest speed. Further movement of the arm from stud to stud increases 110 the voltage 20 volts at a time until the maximum is reached.

115 It will be seen from the foregoing that the speed of rotation of the turntable may be varied by two independent mechanisms so that a very fine adjustment of the tone of the sound reproduced is possible.

The circular attachment plate 62 is preferably secured in position by clamps 62^a fastened to the motor board by screws 62^b, 120 felt silencers 62^c being inserted between clamps and motor board in positions straddling the edge of the attachment plate.

Operation.

125 The operation of a machine constructed according to my invention is as follows:

A record having been placed in position upon the turn-table the tone arm is positioned at the inner end of the sound groove of the record and the abutment link 107 130

shifted to the right until the trip arm 109 engages the left end of the slot 120. The tone arm is then returned to its starting position and the switch 73 closed through lever 82. The closing of the switch sets the motor in motion and through friction roller 12 disc 40 and shaft 300 rotating the turn-table 61. As the turn table with the record rotates the tone arm of course swings 10 towards the center of the same and this movement causes the trip arm 109 to move towards and finally engage the left end of the slot in the abutment link 107. This engagement exerts a thrust upon the short arm 15 of the bell crank lever of which the trigger 90 is a component part, thereby moving the latter away from the disc 82' permitting the latter to snap back to the "off" position, with the consequent opening of the switch 20 and stopping of the machine.

When it is desired to vary the speed of rotation of the turn table the pointer 32 is moved to the graduation indicating the desired speed on the dial 34, this movement 25 through the shaft 20 and arm 35 moving the friction roller towards or away from the center of the disc 40 and consequently varying the speed at which the latter is driven. Further adjustment may then be obtained 30 by increasing or decreasing the voltage of the current of the motor circuit by adjusting arm 202.

What I claim is as follows:

1. In a sound reproducing machine, a 35 driving shaft having a longitudinal feather-way, a disc rotatable on an axis perpendicular to the shaft, a roller mounted on the shaft and rotatable therewith and movable axially thereon, said roller being in rotative engagement with the disc and movable radially relatively thereto, a feather adapted for unisonal movement with said roller and movable longitudinally within said feather-way, a spring yieldingly maintaining the 40 roller in position at one end of its axial travel and manually operable means for moving the roller axially against the resistance of the spring.

2. In a sound reproducing machine, a 50 driving mechanism consisting of a rotary disc, a motor having a shaft in juxtaposition with the disc and disposed perpendicularly to the axis thereof, a sleeve mounted upon and in telescopic relation with the end 55 of the shaft nearest the disc and adapted to normally form an axial extension of the shaft, and to rotate in unison therewith, a roller secured upon that portion of the sleeve which constantly encircles the shaft 60 irrespective of the position of the sleeve, said roller being in rotative engagement with the disc and movable with the sleeve radially relatively to the disc and a spring yieldingly maintaining the roller and sleeve 65 at the end of their travel in which they are

nearest the axis of the disc, and means for moving the roller and sleeve radially relatively to the disc.

3. In a machine of the type described, a 70 motor having a shaft, a sleeve mounted upon and in telescopic relation with the free end of the motor shaft and adapted to form an axial extension thereof, said motor shaft having a longitudinal featherway, a feather carried by said sleeve and movable longitudinally within the featherway, a pair of spaced flanges upon that portion of the sleeve which constantly encircles the motor shaft irrespective of the position of the sleeve, a roller secured upon the sleeve between the flanges, a spring for yieldingly maintaining the sleeve at one end of its axial travel on the shaft, and means for adjusting the sleeve axially against the resistance of 75 the spring.

4. In a sound reproducing machine, a 80 frame, a motor suspended therefrom and having a shaft, a shaft disposed perpendicularly to the motor shaft and adapted to support a turn table at its upper end, a friction disc secured upon the lower end of the turn table shaft, a sleeve mounted upon and in telescopic relation with the free end of the motor shaft and adapted to normally form an axial extension thereof, said 90 motor shaft having a longitudinal featherway, a feather carried by said sleeve and movable longitudinally within the featherway, a pair of spaced flanges upon that portion of the sleeve which constantly encircles the motor shaft irrespective of the position of the sleeve, a roller secured upon the sleeve between the flanges and in rotative engagement with the disc, a spring for 95 yieldingly maintaining the sleeve at one end of its axial travel on the shaft, and means adapted to engage said sleeve for the purpose of adjusting the roller radially relatively to the disc and against the resistance of the spring.

5. In a sound reproducing machine, a 100 frame, a motor suspended therefrom and having a shaft, a shaft disposed perpendicularly to the motor shaft and adapted to support a turn table at its upper end, a friction disc secured upon the lower end of the turn table shaft, a sleeve mounted upon and in telescopic relation with the free end of the motor shaft and adapted to normally form an axial extension thereof, said 105 motor shaft having a longitudinal featherway, a feather carried by said sleeve and movable longitudinally within the featherway, a pair of spaced flanges upon that portion of the sleeve which constantly encircles the motor shaft irrespective of the position of the sleeve, a roller secured upon the sleeve between the flanges and in rotative engagement with the disc, a spring 110 for yieldingly maintaining the sleeve at one 115 end of its axial travel on the shaft, and means adapted to engage said sleeve for the purpose of adjusting the roller radially relatively to the disc and against the resistance of the spring.

6. In a sound reproducing machine, a 120 frame, a motor suspended therefrom and having a shaft, a shaft disposed perpendicularly to the motor shaft and adapted to support a turn table at its upper end, a friction disc secured upon the lower end of the turn table shaft, a sleeve mounted upon and in telescopic relation with the free end of the motor shaft and adapted to normally form an axial extension thereof, said 125 motor shaft having a longitudinal featherway, a feather carried by said sleeve and movable longitudinally within the featherway, a pair of spaced flanges upon that portion of the sleeve which constantly encircles the motor shaft irrespective of the position of the sleeve, a roller secured upon the sleeve between the flanges and in rotative engagement with the disc, a spring 130 for yieldingly maintaining the sleeve at one

end of its axial travel on the shaft, said spring contained within the sleeve and bearing therebetween and the adjacent end of the motor shaft, and means adapted to engage said sleeve for the purpose of adjusting the roller radially relatively to the disc and against the resistance of the spring.

6. In a sound reproducing machine, a frame, a motor suspended therefrom and having a shaft, a shaft disposed perpendicularly to the motor shaft and adapted to support a turn table at its upper end, a friction disc secured upon the lower end of the turn table shaft, a sleeve mounted upon and in telescopic relation with the free end of the motor shaft and adapted to normally form an axial extension thereof, said motor shaft having a longitudinal featherway, a feather carried by said sleeve and movable longitudinally within the featherway, a pair of spaced flanges upon that portion of the sleeve which constantly encircles the motor shaft irrespective of the position of the sleeve, a roller secured upon the sleeve between the flanges and in rotative engagement with the disc, a spring for yieldingly maintaining the sleeve at one end of its axial travel on the shaft, a point of a comparatively soft material mounted in the free end of said sleeve, and means adapted to engage said point for the purpose of adjusting the roller radially relatively to the disc and against the resistance of the spring.

7. In a sound reproducing machine, a frame, a motor suspended therefrom and having a shaft, a shaft disposed perpendicularly to the motor shaft and adapted to support a turn table at its upper end, a friction disc secured upon the lower end of the turn table shaft, a sleeve mounted upon and in telescopic relation with the free end of the motor shaft and adapted to normally form an axial extension thereof, said motor shaft having a longitudinal featherway, a feather carried by said sleeve and movable longitudinally within the featherway, a pair of spaced flanges upon that portion of the sleeve which constantly encircles the motor shaft irrespective of the position of the sleeve, a roller secured upon the sleeve between the flanges and in rotative engagement with the disc, a spring for yieldingly maintaining the sleeve at one end of its axial travel on the shaft, means adapted to engage said sleeve for the purpose of adjusting the roller radially relatively to the disc and against the resistance of the spring and means for yieldingly maintaining the roller in the adjusted position.

8. In a sound reproducing machine, a frame, a motor suspended therefrom and having a shaft, a shaft disposed perpendicularly to the motor shaft and adapted to

support a turn table at its upper end, a friction disc secured upon the lower end of the turn table shaft, a sleeve mounted upon and in telescopic relation with the free end of the motor shaft and adapted to normally form an axial extension thereof, said motor shaft having a longitudinal featherway, a feather carried by said sleeve and movable longitudinally within the featherway, a pair of spaced flanges upon that portion of the sleeve which constantly encircles the motor shaft irrespective of the position of the sleeve, a roller secured upon the sleeve between the flanges and in rotative engagement with the disc, a spring for yieldingly maintaining the sleeve at one end of its axial travel on the shaft, a point of a comparatively soft material mounted in the free end of said sleeve, means adapted to engage said point for the purpose of adjusting the roller radially relatively to the disc and against the resistance of the spring, and means for yieldingly maintaining the roller in the adjusted position.

9. In a sound reproducing machine, a frame, a motor suspended therefrom and having a shaft, a sleeve mounted upon and in telescopic relation with the free end of the motor shaft and adapted to form an axial extension thereof, said motor shaft having a longitudinal featherway, a feather carried by said sleeve and movable longitudinally within the featherway, a pair of spaced flanges upon that portion of the sleeve which constantly encircles the motor shaft irrespective of the position of the sleeve, a roller secured upon the sleeve between the flanges, a spring for yieldingly maintaining the sleeve at one end of its axial travel on the shaft, and means for adjusting the sleeve axially against the resistance of the spring, said last mentioned means consisting of a shaft mounted in said frame and carrying a spring seat, a spring encircling said shaft and bearing tightly between the frame and seat for the purpose of yieldingly maintaining the shaft in any position to which it may be turned, a curved arm having one end secured to said shaft and having its opposite end disposed substantially at right angles to and in bearing relation with said sleeve and a manually operated adjusting arm connected to said shaft.

10. In a sound reproducing machine, a frame, a motor, a turn table, means effecting a rotative connection therebetween, said last mentioned means including a friction disc and a roller in rotative engagement with the disc and adjustable radially relatively thereto, and means for radially adjusting said roller, said means consisting of a shaft, a curved arm having one end connected to and being carried by said shaft and having its opposite end operatively connected to the roller, said shaft having a

squared portion, an adjusting arm rigidly mounted upon the squared portion of the shaft, a spring seat carried by said shaft and a spring bearing tightly between the frame and seat and adapted to maintain the shaft in any position to which it may be turned.

11. In a sound reproducing machine, a frame, a motor, a turn table, means effecting a rotative connection therebetween, said last mentioned means including a friction disc and roller in rotative engagement with the disc and adjustable radially relatively thereto and means for radially adjusting said roller, said means consisting of a shaft, an arm having one end connected to said shaft and having its opposite end operatively connected to the roller, and adjusting arm secured to said shaft and carrying a pointer and finger-hold at its free end, a graduated dial positioned adjacent said pointer, a spring seat carried by said shaft and consisting of a pair of slots formed in said shaft diametrically opposite each other, a horseshoe plate straddling the shaft and seated in said slots and a cup-shaped washer encircling the shaft and plate and a spring encircling the shaft and bearing tightly between the frame and washer and adapted to maintain the shaft in any position to which it may be turned by said adjusting arm.

12. In a sound reproducing machine a supporting frame having an opening, a bushing vertically positioned within the opening, a motor suspended from said frame, a vertically disposed shaft mounted in said bushing and adapted to support a turn table at its upper end, a lubricating washer encircling the shaft and resting upon the upper end of the bushing, an anti-friction washer encircling the shaft and resting upon the lubricating washer, and a collar mounted in fixed position upon the shaft and adapted to rest upon the anti-friction washer, the lower end of said shaft being free and reduced and threaded, and means effecting a rotative connection between the motor and shaft, said means including a roller driven by said motor and a disc in frictional engagement with the roller and secured upon the reduced lower end of said shaft.

13. In a sound reproducing machine a supporting frame having an opening, a bushing vertically positioned within the opening, a motor suspended from said frame, a vertically disposed shaft mounted in said bushing and adapted to support a turn table at its upper end, a lubricating washer encircling the shaft and resting upon the upper end of the bushing, an anti-friction washer encircling the shaft and resting upon the lubricating washer, and a collar mounted in fixed position upon the shaft and adapted to rest upon the anti-friction washer, the lower end of said shaft being free and re-

duced and threaded and means effecting a rotative connection between the motor and shaft, said means including a roller driven by said motor and a disc in frictional engagement with the roller and secured upon the reduced lower end of said shaft, said disc consisting of a unitary casting having a hub as an integral part thereof with an opening to receive the reduced lower end of the shaft, and a nut screwed upon said reduced end and clamping the disc in position thereon.

14. In a sound reproducing machine a turntable, a motor for driving the same, and means for starting and automatically stopping the motor consisting of a circuit including the motor and a switch adapted to spring open, a manually operated lever for closing the switch, a trigger pawl adapted to engage the lever for the purpose of maintaining the latter in position with the switch closed, means for yieldingly maintaining the lever and pawl in engagement with each other, and means for moving the pawl away from the lever when the latter is in position closing the switch for the purpose of releasing the switch.

15. In a sound reproducing machine a turntable, a motor for driving the same, and means for starting and automatically stopping the motor, consisting of a circuit including the motor, a switch included in the circuit and consisting of a fixed contact and a spring contact adapted to be moved into engagement therewith, a cam adapted to move the movable contact, a manually operated lever for actuating the cam, means for retaining the lever in position closing the switch, and means for automatically releasing the lever.

16. In a sound reproducing machine, a tone arm, a turntable, a motor for driving the same and means for starting and automatically stopping the motor, consisting of a circuit including the motor and a switch adapted to spring open, a manually operated lever for closing the switch, a trigger pawl adapted to engage the lever for the purpose of maintaining the lever in position with the switch closed, means for yieldingly maintaining the lever and pawl in engagement with each other, and trip mechanism actuated by the tone arm for moving the pawl away from the lever when the latter is in position closing the switch for the purpose of releasing the switch.

17. In a sound reproducing machine a tone arm, a turntable, a motor for driving the same, and means for starting and automatically stopping the motor consisting of a circuit including the motor, a switch included in the circuit and consisting of a fixed contact and a spring contact adapted to be moved into engagement therewith, a cam adapted to move the movable contact, a

manually operated lever for actuating the cam, means for retaining the lever in position closing the switch, and trip mechanism actuated by the tone arm for automatically 5 releasing the lever.

18. In a sound reproducing machine a turntable, a motor for driving the same, and means for starting and automatically stopping the motor consisting of a circuit including the 10 motor, a switch included in the circuit and consisting of a fixed contact and a spring contact adapted to be moved into engagement therewith, a cam adapted to move the movable contact, a manually operated lever 15 for actuating the cam, a trigger pawl adapted to engage the lever for the purpose of maintaining the lever in position with the switch closed, means for yieldingly maintaining the lever and pawl in engagement 20 with each other, and means for moving the pawl away from the lever when the latter is in position closing the switch for the purpose of releasing the switch.

19. In a sound reproducing machine a tone arm, a turntable, a motor for driving the same, and means for starting and automatically stopping the motor, consisting of a circuit including the motor, a switch included in the circuit and consisting of a 25 fixed contact and a spring contact adapted to be moved into engagement therewith, a cam adapted to move the movable contact, a manually operated lever for actuating the cam, said lever having a tooth, a trigger pawl adapted to engage the tooth, means for yieldingly maintaining the lever and pawl in engagement with each other, and means for moving the pawl away from the lever when the latter is in position closing the 30 switch, said last mentioned means consisting of trip mechanism actuated by the tone arm and operatively connected to the pawl.

20. In a sound reproducing machine a tone arm, a turntable, a motor for driving the same, and means for starting and automatically stopping the motor, consisting of an electric circuit including the motor and a switch, a manually operated switch closing member, a bell-crank lever having a trigger 45 arm adapted to retain the switch closing member in position with the switch closed, a spring yieldingly maintaining the trigger arm in engagement with said member, and trip mechanism actuated by the tone arm and operatively connected to the other arm 50 of the bell-crank lever.

21. In a sound reproducing machine, a turntable, means for rotating the same, movable means adapted, when in one position, to prevent rotation of the turntable and when in another position to permit such rotation, a pawl adapted to yieldingly maintain the last mentioned means in position permitting rotation of the turntable, and an adjustable 60 trip operatively connected to the pawl for

automatically releasing the said last mentioned means, the adjustment of said trip being unaffected by movement of said last-mentioned means.

22. In a sound reproducing machine a turntable, a motor for driving the same, and means for starting and automatically stopping the motor consisting of a circuit including the motor, a switch included in the circuit and consisting of a fixed contact and a spring contact adapted to be moved into engagement therewith, a cam adapted to move the spring contact, a manually operated lever for actuating the cam, said lever having a toothed portion, a bell-crank lever 75 one arm of which constitutes a pawl adapted to engage the toothed portion for the purpose of retaining the lever in position closing the switch, a spring yieldingly maintaining the pawl and manually operated lever in engagement with each other, and trip mechanism operatively connected to the other arm of the bell crank and adapted to move the pawl away from the lever for the purpose of automatically opening the switch. 80

23. In a sound reproducing machine a tone arm, a turntable, a motor for driving the same, and means for starting and automatically stopping the motor consisting of a circuit including the motor, a switch included in the circuit and consisting of a fixed contact and a spring contact adapted to be moved into engagement therewith, a cam adapted to move the spring contact, a manually operated lever for actuating the cam, said lever having an irregular edge, a bell-crank lever one arm of which constitutes a pawl adapted to engage the said edge for the purpose of retaining the lever in position closing the switch, the irregularity of said edge being such that the position of the pawl when retaining the lever in position closing the switch is exactly the same as its position after the lever has been released, a spring yieldingly maintaining the pawl and manually operated lever in engagement with each other, and trip mechanism operatively connected to the other arm of the bell crank and adapted to move the pawl away from the lever for the purpose of automatically opening the switch, said trip mechanism consisting of a member adjustably mounted upon the said other arm of the bell crank, means for creating frictional resistance to relative movement between the member and said last-mentioned arm, an abutment adjustably mounted upon said member, and a trip mounted upon the tone arm and movable in a path intersected by the abutment. 95

24. In a sound reproducing machine a movable tone arm, a turntable, a motor for driving the turntable, and means for starting and automatically stopping the motor, consisting of an electric circuit including the 100

- motor and a switch, means for closing the switch, and means for automatically opening the switch including a trip arm mounted upon and movable with the tone arm and an adjustable abutment located in the path of the trip arm and operatively connected to the switch closing means.
25. A unitary attachment for sound reproducing machines consisting of an attachment plate, a switch mounted upon the attachment plate, a manually operated switch-closing member pivoted upon the attachment plate, a bell crank lever pivoted upon the attachment plate and having a trigger arm adapted to retain the switch closing member in position with the switch closed, means for yieldingly connecting the switch-closing member and trigger arm, and an adjustable device mounted upon the other arm of the bell crank lever and adapted when subjected to a slight thrust to release the switch-closing member from the trigger arm permitting the opening of the switch.
26. A unitary attachment for sound reproducing machines comprising an attachment plate, a switch mounted upon the attachment plate and having a fixed contact and a spring contact movable to and from engagement with the fixed contact, a manually operated lever having one end enlarged and pivoted upon the attachment plate, such enlarged end being notched, a cam of insulating material rigidly mounted upon said enlarged end and movable in unison therewith, and adapted to move said spring contact, a turn table engaging stop mounted upon said lever and movable in unison therewith, a bell crank lever pivoted upon the attachment plate and having a trigger arm terminating in a pawl adapted to engage an irregular portion of said lever end for the purpose of retaining the latter in position closing the switch, a spring effecting a yielding connection between the trigger arm and said lever and adapted to maintain the same in bearing relation with each other, a trip device adjustably mounted upon the other arm of said bell crank lever, said device consisting of a member pivoted upon the said arm and insulated therefrom, means for creating a frictional resistance to relative movement therebetween and an abutment link pivoted upon said member.
27. In a sound reproducing machine, a frame having a vertical bearing comprising a bore having a portion of increased diameter to provide a seat, a lubricating washer positioned upon said seat, an anti-friction washer positioned upon said lubricating washer, a motor suspended from said frame, a vertically disposed shaft rotatably mounted in said bearing, said shaft having a collar adapted to rest upon said seat and having a reduced lower end which is threaded and projects beyond the lower end of the bore, and means rotatively connecting the motor to the shaft consisting of a roller on the motor shaft and a disc in frictional engagement with the roller and mounted upon the reduced end of the shaft, and a nut screwed upon said end and securing the disc in place.
28. In a sound reproducing machine, a frame having a vertical bearing comprising a bore having a portion of increased diameter to provide a seat, a lubricating washer positioned upon said seat, an anti-friction washer positioned upon said lubricating washer, a motor suspended from said frame, a vertically disposed shaft rotatably mounted in said bearing, said shaft having a collar adapted to rest upon said anti-friction washer and having a reduced lower end which is threaded and projects beyond the lower end of the bore, and means rotatively connecting the motor to the shaft consisting of a roller on the motor shaft and a disc in frictional engagement with the roller and mounted upon the reduced end of the shaft, and a nut screwed upon said end and securing the disc in place.
29. In a sound reproducing machine, a frame having a bearing comprising a conical enlargement forming an integral part of the frame, such enlargement having a vertical boring therethrough, the end of which is of increased diameter to provide a pair of annular seats one located at the extreme upper end and the other at a slight distance beneath the same, a bushing mounted in the reduced portion of said boring with its upper end forming a seat, a lubricating washer positioned upon said seat, an anti-friction washer positioned upon said lubricating washer, a shaft rotatably mounted in said bushing and having a collar adapted to rest upon the top of the anti-friction washer for the purpose of limiting downward movement of the shaft, that portion of the shaft within the bushing being reduced to provide a lubricating chamber, and a cupped washer located upon the upper seat in position encircling the shaft and adapted to retain a lubricant within the encircling space, a turn table mounted upon the upper end of the shaft, and means for driving the shaft.
30. In a sound reproducing machine a motor board having an opening therein, and a unit adapted to be mounted thereon in position within the opening said unit consisting of a circular attachment plate of a diameter larger than the opening and adapted to rest upon the top of the motor board, a frame connected to the attachment plate, a turntable shaft mounted in the frame, a motor suspended from the frame, a friction drive between the motor and shaft, and mechanism mounted upon the attachment plate for starting and automatically stopping the motor.
31. In a sound reproducing machine, a

turntable, a motor for driving the same, an electric circuit including said motor, and means for adjusting the speed of rotation of the turntable, said means consisting of a variable resistance included in the motor circuit.

32. In a sound reproducing machine, a turntable, a turntable shaft, a motor, a friction drive between said motor and shaft, means for relatively adjusting the friction elements for varying the speed of rotation

of the turntable and means for varying the said speed independently of the said adjusting means, consisting of a variable resistance included in the motor circuit. 15

In testimony whereof I have signed my name to this specification in the presence of two witnesses.

ELMER A. FARMER.
